US00D744455S

(12) **United States Design Patent**
Huang

(10) **Patent No.:** **US D744,455 S**
(45) **Date of Patent:** **** Dec. 1, 2015**

(54) **VIBRATION UNIT FOR ACOUSTIC MODULE**

(71) Applicant: **Tang Band Industries Co., Ltd.**, Ningbo (CN)

(72) Inventor: **Hsin Min Huang**, Ningbo (CN)

(73) Assignee: **Tang Band Industries Co., Ltd.**, Ningbo, Zhejiang (CN)

(**) Term: **14 Years**

(21) Appl. No.: **29/488,389**

(22) Filed: **Apr. 18, 2014**

(51) LOC (10) Cl. **14-01**

(52) U.S. Cl.

USPC **D14/222**; D14/204

(58) **Field of Classification Search**

USPC D14/204, 210–216, 221, 222, 172; 181/143, 144, 147, 148, 150–153, 157, 181/198, 199; 381/300–303, 306, 332, 333, 381/336, 345, 361–364, 386–388

CPC H04R 7/00; H04R 7/045

(57) **CLAIM**

The ornamental design for a vibration unit for acoustic module, as shown and described.

DESCRIPTION

FIG. 1 is a perspective view of a vibration unit for acoustic module showing my new design.

FIG. 2 is a top plan view thereof.

FIG. 3 is a bottom plan view thereof, wherein the broken line portion of the figure drawing is included to show unclaimed subjected matter only and forms no part of the claimed design.

FIG. 4 is a left side elevational view thereof.

FIG. 5 is a right side elevational view thereof.

FIG. 6 is a front elevational view thereof; and,

FIG. 7 is a rear elevational view thereof.
